UNITED STATES PATENT OFFICE.

WILLIAM E. TURNER, OF ROCHESTER, NEW YORK, ASSIGNOR TO IDEAL FIRE ESCAPE CO., OF ROCHESTER, NEW YORK, A CORPORATION OF NEW YORK.

FIRE-ESCAPE.

936,193.

Specification of Letters Patent.

Patented Oct. 5, 1909.

Application filed September 19, 1908. Serial No. 453,745.

To all whom it may concern:

Be it known that I, WILLIAM E. TURNER, a citizen of the United States of America, residing at Rochester, in the county of Monroe and State of New York, have invented 5 new and useful Improvements in Fire-Escapes, of which the following is a specification.

This invention relates to fire escapes, and 10 one of the principal objects of the same is to provide a simple, reliable and efficient fire escape which is not accessible to thieves or robbers but which can be instantly made accessible to occupants of the house or building.

Another object of the invention is to provide a fire escape in which the cables for lowering the occupants are wound upon spools or drums and locked in this position 20 until they are needed for use and which will be instantly unwound upon turning a crank or handle in case of fire.

Still another object of the invention is to provide a fire escape which is held in position 25 in a casing near the top of a building and which can be instantly rendered accessible by turning a crank or handle and in which the movement of said crank or handle will throw an electric switch to ring a bell 30 or all the bells in the building to alarm the occupants.

Another object of the invention is to provide an improved gripping device for engaging the cable to permit the occupant to 35 descend with safety to the ground.

These and other objects may be attained by means of the construction illustrated in the accompanying drawings, in which,—

Figure 1 is a front elevation of a building 40 provided with a fire escape made in accordance with my invention. Fig. 2 is a vertical sectional view taken on the line 2—2 of Fig. 1, and looking in the direction indicated by the arrows. Fig. 3 is a similar 45 view taken on the line 3—3 of Fig. 1, looking in the direction indicated by the arrows. Fig. 4 is a perspective view of the cable grip. Fig. 5 is a central longitudinal section through the same. Fig. 6 is a horizontal 50 section on the line 6—6 of Fig. 5, looking in the direction of the arrow.

Referring to the drawings, the numeral 1, Fig. 1, designates the wall of a building, and located near the roof of a building is a 55 casing 2 which is designed to inclose the

operative mechanism of my fire escape. Journaled in suitable brackets 3 is the main shaft 4, said shaft having secured at suitable intervals thereon spools or drums 5. Wound upon these drums are cables 6, said 60 cables each having a weight 7 on the lower end thereof, said cables passing through openings in the bottom of the casing 2. To wind the cables 6 upon the spools 5 a sprocket wheel upon the shaft 4 is provided 65 with a sprocket chain 8 which extends through the wall 1 of the building and upon the inside of the building suitable brackets 9 are secured, and journaled in said brackets is a sprocket wheel 10 around which the 70 chain 8 passes. A suitable crank 11 is provided for rotating the sprocket wheel 10 and winding the cables 6 upon the spools.

For locking the shaft 4 against rotation 75 I have provided a brake comprising a flexible strap 12 secured at one end to a pin 13 and at the other end connected to a yoke 14, said yoke being pivoted at 15 to brackets 3. The strap 12 is connected to a pin 16 which extends across the yoke 14.

Formed integral with the yoke 14 is an inclined lever 17 having a curved portion 18. To hold the brake strap 12 firmly 80 against the brake wheel 19 a weight 20 is provided with oppositely disposed brackets 85 21 in which is journaled a pintle 22 carrying a roller 23. The pintle 22 extends outward at opposite sides of the brackets 21, and to engage and hold the weight in its upper position to press downward upon the 90 lever 17 a double latch 24 having hooked ends which engage the pintle 22 straddles the brackets 21 on the weight, said latch being pivoted at 25 to lugs on a bracket 26.

Pivoted at 27 to the latch is a connection 28, the lower end of which is pivotally connected at 29 to a lug 30 formed on a shaft 31 journaled in the brackets 3. Formed on the shaft 31 are lugs 32, and connected to these lugs is a wire or cable 33 which extends through a suitable tube or housing 34 to a crank arm 35 secured to a shaft 36 mounted in a bearing extending through the wall 1 of the building and provided upon its inner end with a crank arm 36 inclosed within a 100 cap or housing 37. One of the lugs 32 has connected to it a wire or suitable flexible device 38 connected at its lower end to an arm 39 connected to a shaft 40 which may be rotated by means of a crank 41 having a 105 110

contact 42 upon one end adapted to be swung into contact with the terminals 43 of electric wires 44 for ringing bells in the building.

- 5 Referring to Figs. 4, 5 and 6, in which I illustrate my improved cable grip, the letter *a* designates the casing of the grip provided with an extension *b* having a slot *c* through which a strap *d* is passed, said strap having 10 a snap hook *e* and a ring *f* connected to the ends thereof. In the ends of the casing *a* rounded openings *g* are formed. Hinged at *h* to the casing *a* is a cover *i*, and pivoted between projecting lugs *j* on the cover is a 15 hand lever *k*, said lever having spaced projections *l* extending through an opening *m* in the cover. The terminal ends of the projections *l* are beveled upon their inner edges, as at *n*, and journaled between the projections *l* is a roller *o* having a roughened or corrugated periphery, said roller being journaled upon the pin *p*. A stop *q* on the end of the lever *k* serves to limit the outward swing of said lever. To hold the cover *i* 20 in closed position a sliding latch *r* provided with a slot *s* is connected to the side of the casing by means of a screw *t*, said latch being provided with an angular arm *u* having a terminal angular lug *v* which engages the cover *i* to hold it closed. When it is desired 25 to open the cover *i* to connect the grip with the cable 6 the screw *t* is turned until the latch is permitted to slide and carry the lug *v* beyond the end of the casing.
- 30 35 The operation of my invention may be briefly described as follows:—When a fire is discovered in the building, any person upon any of the floors can turn the crank 36 which will pull downward upon the wire 40 or cable 33 to rock the shaft 31 and pull downward upon the connection 28 to operate the latch 24, raising the hooked portions of said latch from the pintle 22 of the weight 20, said weight then rolling down to the 45 dotted line position in Fig. 3 to permit the inclined portion 17 of the lever to occupy the position shown in dotted lines and to relieve the brake wheel 19 of the stress applied thereto by the strap 12. The shaft 4 50 thus being relieved of the brake pressure, the weights 7 will descend and carry with

them the cables 6 to the ground, and at the same time the electric bells throughout the building will be started to ring by means of the operation of the switch 42. It is to 55 be noted that the cables 6 extend immediately in front of the windows of the building. Occupants may readily connect the grips to the cables 6 and can let themselves gradually to the ground, regulating the 60 speed by means of the hand lever 12.

From the foregoing it will be obvious that my fire escape is comparatively simple in construction, cannot readily get out of order, is insured against the depredations 65 of thieves or robbers, is entirely inclosed against inclement weather and is instantly rendered operative in case of fire.

I claim:—

1. In a fire escape, the combination with 70 a main shaft journaled to brackets secured to a building, of spools on said shaft, cables on said spools, means for winding said cables on said spools, a brake wheel on said shaft, a brake strap applied to said brake 75 wheel, a lever to which said brake strap is connected, a sliding weight for holding said lever in position to apply said brake, a latch for holding said weight in one position, and means connected to said latch extending into 80 position to be operated by occupants of the building.

2. In a fire escape, the combination with a casing, of a shaft journaled to brackets secured to a building within said casing, spools 85 on said shaft, cables on said spools, means for winding said cables on said spools, a brake wheel on said shaft, a brake strap for said wheel, a lever to which said brake strap is connected, a weight for holding said lever 90 in position to apply said brake, a pivoted latch for holding said weight in one position, means connected to said latch and extending into position to be operated by occupants of the building, and a cap or housing 95 for covering said means.

In testimony whereof I affix my signature in presence of two witnesses.

WILLIAM E. TURNER.
